UNITED STATES PATENT OFFICE

FREDERIC H. POOR, OF YONKERS, NEW YORK; ELIZABETH HUBBARD POOR, EXECUTRIX OF SAID FREDERIC H. POOR, DECEASED, ASSIGNOR TO FREDERIC H. POOR, INC., OF NEW YORK, N. Y., A CORPORATION OF NEW YORK

SLING APPARATUS

Application filed September 26, 1928. Serial No. 308,380.

My invention relates to an improved device for use particularly in connection with rope or cable slings and has for one of its objects the provision of a device which is so constructed and arranged as to provide a firm and self-tightening grip on the sling at or adjacent the point in the sling where one end of the loop thereof bears upon the suspending strands.

More specifically my invention is directed to an improved device for use with slings such as those employed in hoisting freight and the like although my invention is capable of many other uses, and provides an apparatus which renders the usual sling much quicker and surer in operation than at present, and also provides against undue lengthening of the sling as tension is placed upon the same when the load to be hoisted is lifted, an advantageous feature at once apparent to anyone experienced in the use of slings in general.

The apparatus constituting my invention may take various forms and several forms have been illustrated.

In the drawings, Fig. 1 shows in front elevation one embodiment of my invention;

Fig. 2 shows the same in side elevation;

Fig. 3 is a section on the line 3—3 of Fig. 1;

Figs. 4 and 5 are views similar to Fig. 3 of modifications; and

Fig. 6 is a view similar to Fig. 1 of a further modification.

Referring first of all to Figs. 1, 2 and 6: 1 designates the usual rope or cable sling which may be either of the endless or of the non-endless type.

Ordinarily in the use of a sling, the material to be handled is first deposited thereon, then one end of the sling is passed through the other end to form a bight about the material to be handled. While this method is almost uniformly used on piers, in freight yards, and the like, it is not entirely satisfactory for the reason that when tension is placed upon the sling by the crane or other hoisting apparatus, the load or material being handled is at such a distance from the hoisting member as to make it difficult to properly deposit the load. The present invention eliminates this drawback to a great extent inasmuch as the

sling may be drawn tightly about the load in the first instance and my device secured to the bight about the load or clamped to the sling in close proximity to the load.

In the embodiment of the invention under consideration my device is provided with a body member or frame 4 having longitudinally converging flanges 5 on its front face.

Between the flanges 5 the body member is slotted at 6, this slot receiving a slide 7. The slot 6 extends in the direction of pull on the device.

Integral with the slide 7 or at least rigidly secured thereto is a wedge shaped clamping member 8 adapted to cooperate with the flanges 5 on the block 4.

Secured to the slide 7 and hence to the clamp member 8, but on the side of the body member 4 opposite the clamp member is a member 9, the lower end of which is provided with a hook 10, this hook preferably extending transversely of the device.

The upper end of the body member 4 is shaped as shown at 11 to be readily engaged by the hook of the crane or other hoisting apparatus used in connection with the device.

In use the sling 1 may be placed about the load 12 in the usual way, the loop 3 being passed through the loop 2 as shown on Fig. 2, and the latter hooked over the hook 10 on the member 9. The loop 3 is pulled upwardly until the sling is drawn as tightly as possible about the load, and the suspending strands thereof placed in the space between the wedge shaped clamping member 8 and the flanges 5 on the block 4.

When the crane or other hoisting apparatus is connected to the hook 11 it will be apparent that the block 4 will tend to move upwardly with respect to the wedge member 8 and consequently the suspending sides of the sling designated 13 and 14 will be securely clamped between the sides of the wedge and the flanges 5.

It is to be noted that the sides or faces 15 of the flanges 5 adjacent the wedge member 8 are inclined and that the sides of the clamping wedge 8 are inclined in the same general direction, as indicated at 16, but at a different angle from the inclination of the faces 15

of the flanges 5. I find that this gives me an increased grip of the clamping wedge 8 on the sides 13 and 14 of the sling. However, the shape of the space between the wedge 5 faces and the inside of the flanges 5 may be varied as I have indicated in Figs. 4 and 5.

In Fig. 4 the sides or faces 15 of the flanges 5 adjacent the sides 16 of the member 8 are straight, i. e., parallel to the outer faces of the flanges 5. Likewise the sides 16 of the clamping wedge 8 are parallel with the faces 15.

In Fig. 5 I have modified somewhat both the inner and outer faces of the flanges 5, these changes in this instance being provided by curving the outside of the member 4 and making the inside faces 15 concave, the radius of this concave portion being approximately equal to that of one of the strands of the sling. Likewise the clamping wedge 8 has been concaved on its faces 16, the radius of these concave faces being also approximately that of one of the strands of the sling.

These are various formations which may be employed in making up my device but in all cases I retain the essential feature of providing on one face of the member 4 a wedge formation for clamping the sides of the sling, means being provided whereby when tension is placed upon the device the wedge will tighten upon the strands of the sling.

In Fig. 6 I have illustrated a still further modification of my invention in which I have provided an apparatus which is particularly designed for use with a sling which is not of the endless type. In this embodiment of my invention one end of the sling is brought up to one side of the hook 10, a half or a full turn being taken around the member 9 and then led upwardly and placed between the wedge 8 and flanges 5 on the block 4. In passing upwardly to this position one strand of the sling is passed under a hook 17 provided on the member 9. The other end of the sling is around the load and placed between the wedge 8 and the other flange 5. Tension on the device will wedge both leads of the sling between the clamping wedge 8 and the flanges, the one-half turn taken about the member 9 and the hook 17 functioning to resist upward movement of the member 9 and hence of the wedge 8 in a manner analogous to the hooking of the bight 2 over the hook 10 in the other form of my invention above described.

In all the forms of my invention, therefore, it will be seen that I have provided a plate or block having converging flanges or their equivalent on one face, means being provided between these flanges for pinching or clamping the material of the sling between this means and the flanges. It will be seen also that the pinching or clamping means is provided with a hook or its equivalent by

which the sling is attached thereto to assist in bringing about this action.

As above explained, the device as a whole may be used with a loop sling such as is shown in Fig. 1 or with a single rope sling as illustrated in Fig. 6, or either device may be used with either the endless or the non-endless type of sling.

What I claim is —

1. Sling apparatus for the attachment of a sling to hoisting apparatus comprising in combination a body member adapted to be attached to the hoisting apparatus, a clamping member carried thereby and cooperating therewith and adapted to clamp the sling between it and the body member, and means carried by the clamping member for attachment to the free end of the sling, whereby a pull on the sling will increase the clamping action of the clamping member.

2. Sling apparatus for the attachment of a sling to hoisting apparatus comprising in combination a body member adapted to be attached to the hoisting apparatus and provided on one face with flanges, a clamping member lying between said flanges and having movement relatively thereto to clamp the sling, and means carried by the clamping member for engagement with another portion of the sling, whereby relative movement of the body member and clamping member with a consequent increase in the clamping of the sling is assured when tension is placed on the sling.

3. Sling apparatus comprising in combination a body member adapted to be attached to hoisting apparatus, a clamping member movably carried thereby, a sling having one portion clamped between the clamping member and body member and means for the attachment of another portion of the sling to the clamping member, whereby a clamping action on the sling between the body member and clamping member is assured when the sling is under tension.

4. Sling apparatus comprising in combination a flanged body member, a clamping member disposed between the flanges on said body member, said clamping member having a sliding bearing in the body member, one portion of the sling engaging the clamping member only, the suspending strands of the sling being gripped between the clamping member and body member, whereby increase of tension on the sling increases the clamping action on the sling.

5. Sling apparatus comprising in combination a flanged body member adapted for attachment to a hoisting device, a wedge-shaped clamping member cooperating with the flanges of the body member, said clamping member extending through the body member and having a sling-engaging portion on said extension.

6. Sling apparatus comprising in combina-

- tion a body member provided on one face with convergent flanges, a wedge-shaped clamping member slidably mounted in the body member and cooperating with the said convergent flanges, an extension on said clamping member passing through the body member and provided with a hook for engagement with the sling.
7. Sling apparatus comprising in combination a body member having converging flanges on one face thereof, a clamping member having converging sides cooperating with said flanges, an extension on the clamping member passing through the body member, and provided with a hook formation for engagement with the sling.
8. Sling apparatus comprising in combination a body member provided on one face with convergent flanges, a clamping member lying between said flanges, the said clamping member having converging sides extending in the same general direction as the said flanges in the plane of the clamping member and at a different angle transversely of said plane.
9. Sling apparatus comprising in combination a slotted body member having converging flanges on one face thereof, a clamping member having converging sides lying between said flanges, said clamping member extending through and having a bearing in said slot in the body member, and an extension on said clamping member on the side of the body member opposite the said flanges, provided with a sling engaging hook formation.
10. Sling apparatus comprising in combination a body member having converging flanges on one face thereof, said flanges extending in the general direction of pull on the sling when the device is in use, a clamping member on the flanged face of the body member having converging sides cooperating with said flanges, said body member being provided with a slot through the same and extending in line with the pull on the device, a portion of the clamping member passing through and having a bearing in said slot, said clamping member being provided with a downwardly extending hooked portion for engagement with the sling at the side of the body member opposite the flanges.
11. A sling apparatus comprising in combination a body member having converging flanges on one face thereof, a clamping member on the flange face of the body member having converging sides cooperating with said flanges, said body member and clamping member being movable relatively, means carried by one of said members for attachment thereof to hoisting apparatus, a hook for connection to a sling carried by the other of said members, and a sling having a portion separate from the hook engagement portion clamped between said body member and
- clamping member whereby the lifting of a load carried in said sling will effect an increase in the clamping of the sling between the clamping member and body member.
- This specification signed this 25th day of September, 1928.
